(57) **CLAIM**

We claim the ornamental design for a connector for a P-trap toilet pan, as shown and described.

DESCRIPTION

FIG. 1 is a front perspective view showing the new design.

FIG. 2 is a rear perspective view of the new design.

FIG. 3 is a front view of the new design.

FIG. 4 is a rear view of the new design.

FIG. 5 is a right side view of the new design.

FIG. 6 is a left side view of the new design.

FIG. 7 is a top view of the new design; and,

FIG. 8 is a bottom view of the new design.

The broken line(s) shown in the drawings are for illustrative purposes only and form no part of the claimed design.
